BED

Ernest Herrmann, New York, N. Y., assignor to
 Heywood-Wakefield Company, Gardner, Mass.,
 a corporation of Massachusetts

Application October 8, 1949, Serial No. 5,379

Term of patent 7 years

(Cl. D5—4)

To all whom it may concern:

Be it known that I, Ernest Herrmann, a citizen of the United States, residing at New York, in the county of New York and State of New York, have invented a new, original, and ornamental Design for a Bed, of which the following is a specification, reference being had to the accompanying drawing, forming part thereof, in which:

Fig. 1 is a view in perspective of a bed, showing my new design.

Fig. 2 is a view in end elevation of the bed shown in Fig. 1, as viewed from the foot of the bed.

Fig. 3 is a view in end elevation of the bed shown in Fig. 1, as viewed from the head of the bed.

Figs. 4 and 5 are fragmentary views in side elevation, on an enlarged scale, of the head and foot of the bed shown in Fig. 1.

I claim:

The ornamental design for a bed, substantially as shown.

ERNEST HERRMANN.
